UNITED STATES PATENT OFFICE

JAMES W. McKEEVER, OF FLEMINGTON, WEST VIRGINIA, ASSIGNOR OF ONE-TENTH TO GEORGE R. BROWN AND ONE-TENTH TO JOHN A. BRIDGE, OF GRAFTON, WEST VIRGINIA, AND ONE-TENTH TO WILLIAM E. SIMONTON AND THREE-TENTHS TO WILLIAM C. WYCKOFF, OF FLEMINGTON, WEST VIRGINIA.

WRENCH.

No. 801,151.

Specification of Letters Patent.

Patented Oct. 3, 1905.

Application filed April 5, 1905. Serial No. 253,952.

To all whom it may concern:

Be it known that I, JAMES W. McKEEVER, a citizen of the United States, residing at Flemington, in the county of Taylor and State of 5 West Virginia, have invented new and useful Improvements in Wrenches, of which the following is a specification.

This invention relates to a combination nut and pipe wrench, and has for its objects to 10 produce a comparatively simple and inexpensive device of this character in which the gripping-jaws may be readily clamped in engaging position and one in which the jaws will be moved automatically to open position for 15 engagement with the nut or pipe.

A further object of the invention is to provide a device of this type with a tang to be received by a brace or the like and to be further utilized as a screw-driver.

20 To these ends the invention consists in the novel features of construction and combination of parts more fully hereinafter described.

In the accompanying drawings, Figure 1 is a perspective view of a wrench embodying 25 the invention. Fig. 2 is a side sectional elevation of the wrench, the section being taken centrally and longitudinally thereof. Fig. 3 is a transverse section taken on the line 3 3 of Fig. 2.

30 Referring to the drawings, wherein like numerals of reference designate like parts throughout the several views, 1 designates the body or shank of the wrench terminating at one end in a fixed gripping-jaw 2 and at its 35 other end in a reduced portion or section 3, preferably of rectangular form in cross-section and designed for engagement by a brace or other operating member, said section 3 being sharpened, as at 4, for engagement with a 40 screw, while the jaw 2 has its inner face notched or recessed, as at 5, for engagement with a nut and concaved between its ends, as at 6, for engagement with a pipe.

45 Formed in the body 1 of the tool and extending longitudinally thereof is a laterally-opening socket or recess 7, in which is seated the reduced portion or shank 8 of a movable gripping-jaw 9, pivoted, as at 10, upon a transverse pintle or axle disposed adjacent the inner terminal of the shank 8, whereby the jaw

9 may swing toward and from the relatively fixed jaw 2, it being noted that the jaw 9 has its inner face concaved, as at 11, in like manner to the jaw 2 and provided with transversely-extending teeth or serrations 12 for 55 engagement with a pipe, and, furthermore, is recessed, as at 13, for engagement with a nut or the like.

Disposed within the recess 7 between the shanks 1 and 8 of the gripping-jaws is a leaf-spring 14, secured in place by a rivet or other fastening member 15 and acting to normally move the jaws to open position, there being 60 slidably disposed upon the body of the tool a compression member or sleeve 16, which when 65 moved forwardly toward the jaws serves to close the latter against the action of the spring.

In practice when the member or sleeve 16 is moved toward the rear end of the shank 1 the jaws 2 and 9 open automatically under 70 the influence of the spring 14, thereby permitting engagement with the nut or pipe and after such engagement are securely fixed in 75 engaging position by forward movement of the sleeve 16, as heretofore explained. It will be observed that the reduced portion or section 3 of the shank performs the twofold 80 function of a screw-driver and as a tang to be engaged by a brace.

From the foregoing it is apparent that I 80 produce a simple inexpensive device which may be readily manipulated and one which in practice will securely clamp upon a nut or pipe for action thereon, it being understood that slight changes in the details herein set forth 85 may be resorted to without departing from the spirit of the invention.

Having now described my invention, what I 90 claim as new, and desire to secure by Letters Patent, is—

1. In a device of the class described, a pair of relatively movable jaws provided with shanks, one of said shanks having a longitudinally-extending recess for the reception of the other, a spring disposed within the recess 95 between the shanks and adapted for moving the jaws to open position, and a sleeve arranged for sliding movement longitudinally of the shanks and operable for closing the jaws against the action of the spring. 100

2. In a device of the class described, a jaw having a shank of substantially U shape in cross-section presenting a longitudinally-extending recess, a second jaw having a shank disposed and pivoted at one end within the recess, a spring housed in the recess between the shanks and acting on the latter to move the jaws to open position, and a sleeve arranged for sliding movement longitudinally of

the shanks and operable for closing the jaws 10 against the action of the spring.

In testimony whereof I affix my signature in presence of two witnesses.

JAS. W. MCKEEVER.
